MANUAL MASSAGING DEVICE

Amos R. Marty, Marion, Ohio

Application November 14, 1945, Serial No. 628,406

6 Claims. (Cl. 128—24.2)

1

This invention relates to a manual massaging device and more particularly to electrical means for combined massage, light and heat therapy.

Among the objects of the invention is to provide a compact means for electrically applying vibration and massage with heat and light, simultaneously or separately, to living human tissue.

Another object is to protect the radiant element from the disruptive effects of the vibratory mechanism.

Another object is to accelerate the circulation of the blood, stimulate the muscular and vascular systems and build up the nerve force of the human body.

Another object is to provide a more soothing massaging movement than the hammering effect common to most vibrators in this art.

Other objects and advantages will appear as the description proceeds. In the specification and the accompanying drawings, the invention is disclosed in its preferred form. But it is to be understood that it is not limited to this form, because it may be embodied in modifications within the spirit of the invention as defined in the claims following the description.

In the one sheet of drawings:

Fig. 1 is a vertical section on the line 1—1, Fig. 2, of a manual device constructed in accordance with this invention.

Fig. 2 is a plan view from above of the same.

Fig. 3 is a fragmentary detail in front elevation of the massaging assembly.

Fig. 4 is an end view of the same from below.

Fig. 5 is a diagrammatic wiring diagram of the electric circuits.

In detail the structure shown in Fig. 1, comprises the base portion, preferably molded as an integral unit, having the semicircular under handle 1 extending laterally from the cylindrical head 2, open at the bottom 3 and having the horizontal bridge 4 extending across the top. This bridge has the tubular axial pivot 5 extending upwardly therefrom.

The stem 6 extends upwardly and is slidable within this pivot and has the square portion 7 vertically guided in a square hole in the pivot 5. This stem has the integral baffle head 8. The expansion spring 9 is interposed between this head and the bridge 4. The upper end of the stem is threaded to receive the knurled nut 10, for vertically adjusting the stem 6 against the tension of the spring. The nut bears against the top of the upper portion of the cover 12, having the handle extension 13 registering with the lower handle 1 and combining therewith to form an

2

enclosing casing for the motive assembly. The cover is attached to the base by the several screws such as 14, threaded in the sockets 15 in the margins of the base.

5 The oscillating sleeve 16 surrounds the pivot 5 and has the upper and lower antifriction bearings 17, 18 interposed therebetween. This sleeve has the lateral crank 19, channel shape in cross-section. The sleeve is held in adjusted position 10 by the nut 20 threaded on the upper end of the pivot 5, and bears against the top bearing 17.

The head 2 has the axial socket 21 adapted to receive the end of the bulb 22 and make proper electrical contact therewith. This bulb is adjusted vertically by the nut 10, relative to the lower end of the head 2.

Referring to Fig. 3, the sleeve 16, has the vertical lugs 23, 24 integral therewith. These lugs terminate in the segmental heads 25, 26, having 20 external grooves therein at 27, 28. These grooves interlock with the beads formed on the inner faces of the segments 29, 30 that are integral with the massaging ring 31, adapted to engage the skin of the patient being treated. This ring may be 25 round, oval or variously shaped to meet the desired results. In the present instance the ring has the hemispherical protrusions 32 to produce a stretching and kneading effect on the skin.

The lugs 23, 24 have the finger grips 33, 34 protruding into the openings 35, 36 through the wall of the head 2. By pinching the finger grips between the thumb and forefinger the lugs 23, 24, may be bent inwardly, to engage and disengage them from the massage ring at 27, 28.

35 The motor 37 is adjustably mounted within the handle 1, 13 and has the forward end of its shaft projecting within the channel of the crank 19. This end of the shaft is squared or splined to receive the socket 38, longitudinally slidable 40 thereon. The inner end of the socket has the separated flanges 39, 39', thereon.

The trigger 41 is pivoted at 42 to the base, and extends below the handle adjacent the head 2, and has the upwardly extending arm 43 with a 45 yoke head 44, engaging between the flanges 39, 39' for advancing or retracting the socket 38. The spring detent 45 mounted in the base engages notches in the trigger to latch it in adjusted position. The inner end of the socket 38 has the eccentric antifriction roller 46 mounted thereon and engaging the sides of the crank channel at 19, whereby, this crank is oscillated radially in a plane parallel with the surface of the patient's skin being treated.

55 Referring to Fig. 5, the electric current flows

from the generator, not shown, over the wire 40, through the rheostat 41, across the switch 48, through the motor 37, and over the wires 49, 50, back to the source. Also over the wire 51, across the switch 52, through the filament 53 of the lamp 22 and the wire 54 to the return wire 50. The switches 48, 52 are combined within the housing 55 within the handle cover 13 and controlled by the exposed sliding button 56. The switch is so arranged that the motor and filament circuits can be energized independently. That is, the motor and filament may be operative simultaneously, or either may be operated without the other.

The head 2 has perforations such as 57, with similar openings 58 through the cover 13, for ventilation to carry off the heat generated by the filament 53, the greater volume of which is directed downwardly and absorbed by the skin of the patient. The motor 37 is similarly cooled by ventilation through the trigger opening at 59 and upward through the cover openings 58. The under area of the head 2, acts as a baffle to confine the radiated heat of the filament within the head 2, to assist in maintaining the handle 1, 13 at a comfortable temperature.

This invention operates substantially as follows: The operator grasps the handle 1, 13 and gently applies the massage ring 31 to the skin surface of the patient, with the motor 37 running. The eccentric roller 46 causes the crank assembly 16-31 to oscillate, exerting a rubbing and twisting action on the skin as the massage ring 31 is moved about over the skin surface. This novel oscillating action on the skin tends to open the pores and stimulate the underlying nervous system and blood circulation in the capillary and venous network, promoting increased circulation of the blood in the deeper arterial and vascular system because of the localized nervous activity. This in turn is communicated to the whole sympathetic nervous system with a tonic effect on the whole body of the patient, tending to remove the cause of any local discomfort in the region being treated. The oscillation of the massage ring 31, is soothing and relaxing, relieves muscular and nervous tension, a symptom of much so called disease. Differing materially from the common practice of "hammering" the skin with the usual electric vibrators, the vibratory impact of which sets up a defensive tension in the tissues to resist the attack.

Where such therapeutic treatment is indicated, the switch 52 is closed to energize the infra-red filament 53, the rays of which are directed downwardly through the center opening of the ring 31, and penetrate the underlying tissues of the patient. The depth of penetration of the rays and the proximity of the heat applied to the skin is regulated by raising or lowering the bulb 22 by turning the nut 10 to the selected extent. The volume of heat emanating from the filament 53, is regulated by the rheostat 41. This bulb may be silvered or provided with a suitable gold plated parabolic reflector 60 above to direct all the rays downwardly of the enclosed or open filament at 53.

The bulb form of heat source is preferred, but open filaments, and a variety of light rays such as ultra-violet and disinfectant blue lights and other forms of light and heat therapeutic elements may be substituted for the bulb 22.

A wide variety of massaging rings such as 31, are provided as accessories, ranging from a relatively small skin contact, for restricting the application of massage and heat therapy to a small area, accentuated by lowering the filament 53, up

to diameters greater than shown in Fig. 4. For facial and anatomical regions having underlying bone structures, resilient massaging faces may be provided on the ring base 31.

Because of the lateral movement and pressure imposed upon the ring 31, it is important that it be securely attached at 21, 28. It is equally important that it be easily detached when desired, for substitution and for sterilization before use upon other patients.

A particular advantage of the oscillating massage movement, is the absence of mechanical vibration destructive to the heat element 53, which in the present instance is mounted on the static bridge 4 independent of the vibratory or oscillating assembly 16-31.

The degree of oscillation may be increased or diminished at the will of the operator, by moving the trigger 41, to advance or retreat the eccentric 46 relative to the length of the crank 19.

While a rotary motive means 31 has been shown, it will be obvious to those skilled in the art, that the crank 19 could be caused to vibrate between two opposed magnets alternately energized; or the oscillation may be accomplished by equivalent means, without departing from the spirit of the invention as defined in the following claims.

All of the enclosing structure and much of the operative internal structure is designed to be formed in molded plastics or similar dielectric and thermo-insulating materials, except where friction and wear require appropriate materials.

Having thus described this invention and its mode of operation what I claim and desire to secure by Letters Patent is:

1. A manual massaging device comprising a base having an axial pivot thereon; an oscillating member mounted on said pivot; a massaging member mounted on said oscillating member; means for mechanically oscillating said oscillating member; and means for varying the amplitude of oscillation of said oscillating member.

2. A manual massaging device comprising a handle base having a head; an axial pivot on said base and aligned with said head; a sleeve rotatable on said pivot and having a lateral crank; a motive means in the handle of said base and actuating said crank; means for varying the arc of oscillation of said crank; a massaging member on said sleeve beyond said head and having an opening therethrough; and a therapeutic element within said head and having a stem longitudinally adjustable in said pivot, relative to said massaging member.

3. A manual massaging device comprising a handle base having an angular head; an axial pivot on said base and aligned with said head; a sleeve rotatable on said pivot; a motive means in the handle of said base and oscillating said sleeve; means for varying the arc of said oscillation; a massaging member on said sleeve beyond said head and having an opening therethrough; a stem longitudinally adjustable in said pivot and having a baffle thereon substantially the internal diameter of said head; and a therapeutic element on said stem above said opening in the massaging member.

4. A manual massage device comprising a handle base having an angular head; an axial pivot on said base and aligned with said head; a sleeve rotatable on said pivot and having a lateral crank; a motive means in the handle of said base and having an eccentric engagement with said crank and oscillating said sleeve; means for vary-

ing the amplitude of the oscillations of said sleeve; a massaging member on said sleeve beyond said head and having an opening therethrough; and a therapeutic element mounted in and adjustable longitudinally of said head relatively to said massaging member.

5. A manual massaging device comprising a handle base having an angular head; an axial pivot on said base and alined with said head; a sleeve rotatable on said pivot and having a lateral crank; a motive means in the handle of said base and having an eccentric engagement with said crank and oscillating said sleeve; a trigger means pivoted to said base and actuating said eccentric engagement and varying the stroke of said eccentric; a massaging member on said sleeve beyond said head and having an opening therethrough; and a therapeutic element mounted within and adjustable longitudinally of said head relatively to said massaging member.

6. A manual massaging device comprising a handle base having an angular head; an axial

pivot on said base and alined with said head; a sleeve rotatable on said pivot and having a lateral crank; a motive means in the handle of said base and having an eccentric member engaging said crank for oscillating said sleeve; manual means on said base for moving said eccentric member relative to the axis of said crank; and a massaging member mounted on said sleeve.
